UNITED STATES PATENT OFFICE

MAX SHEROVER, OF NEW YORK, N. Y., ASSIGNOR TO GOLDING BROS. COMPANY, INC., OF NEW YORK, N. Y., A CORPORATION OF NEW YORK

DESIGN FOR A MATTRESS COVER

Application filed September 18, 1930. Serial No. 37,015. Term of patent 3½ years.

To all whom it may concern:

Be it known that I, MAX SHEROVER, a citizen of the United States, and a resident of New York, county and State of New York, have invented a certain new, original, and ornamental Design for Mattress Covers, of which the following is the specification, reference being had to the accompanying drawing, forming part thereof.

The figure is a plan view of a mattress cover showing my new design.

I claim:

The ornamental design for a mattress cover substantially as shown.
